CLOISE H. BALDWIN, OF FORT WORTH, TEXAS, ASSIGNOR TO TEXAS STEEL COMPANY,
OF FORT WORTH, TEXAS, A CORPORATION OF DELAWARE.

HOLDUP AND HOLDDOWN.

Application filed January 18, 1927. Serial No. 161,939.

This invention relates to a hold-up and hold-down for pull rods employed in connection with oil and gas well pumping apparatus, and has for its object to provide, in a manner as hereinafter set forth a thoroughly efficient and adequately lubricated hold-up and hold-down for employment in well pumping apparatus.

When pumping a number of oil wells where the power is supplied from a central plant, the wells are operated by attaching them to surface lines running from the power plant to each of the wells. The surface line consists of pull rods suspended or held up a short distance from the ground. At each revolution of the pumping power the rods will move backward and forward and deliver an up and down motion to the pump in the well. By this method a great many wells can be pumped from one central power plant. Very often due to the general lay-out of the property as well as interference from highways, or property lines, it becomes necessary to use hold-ups and hold-downs to keep the lines near the surface of the ground. Heretofore only shallow wells have been pumped by this method, but from time to time greater depth wells are being attached to central power plants, and which necessitates a more rigidly constructed hold-up or hold-down and a more adequate means for lubricating the bearing of the same, and which is obtained and provided for by a hold-up and hold-down in accordance with this invention.

A further object of the invention is to provide a hold-up and hold-down for the purpose referred to and in a manner as hereinafter set forth, and which is comparatively simple in its construction and arrangement, strong, durable, thoroughly efficient in its use, readily set up, and comparatively inexpensive to manufacture.

With the foregoing and other objects in view the invention consists of the novel construction, combination and arrangement of parts as hereinafter more specifically described and illustrated in the accompanying drawings wherein is shown an embodiment of the invention, but it is to be understood that changes, variations and modifications can be resorted to which fall within the scope of the claims hereunto appended.

In the drawings wherein like reference

characters denote corresponding parts throughout the several views:

Figure 1 is a sectional elevation of a hold-up and hold-down, in accordance with this invention, with the pull rods positioned close to the ground.

Figure 2 is a section on line 2—2 Figure 1.

Figure 3 is a vertical sectional view of a hold-up and hold-down, in accordance with this invention, with the pull rods positioned at their maximum elevation.

Figure 4 is a side elevation of a gudgeon employed in the device for positioning the pull rods close to the ground.

Figure 5 is a like view of one of the bearings employed in the device.

Figure 6 is a fragmentary view of the stirrup box employed when positioning the pull rods close to the ground.

Figure 7 is a side elevation of the stirrup box employed when positioning the pull rods at their maximum elevation.

Figure 8 is a side elevation of a single stirrup box.

The term "hold-down" is used to infer the suspending of the pull rods in close proximity to the ground, and the term "hold-up" is to infer the positioning of the pull rods at their maximum elevation.

When using the hold-down or the hold-up, a base 1 is employed having fixedly secured therewith, by the holdfast devices 3, a pair of spaced interiorly threaded, flanged collars 4. The flanges of the collar 4 are indicated at 2 and the holdfast devices 3 extend through the collars 2, and anchor the collars upon the upper face of the base.

Threadably engaging with each collar 4, is a vertically disposed tubular standard 5 of any suitable height and diameter and with the diameter thereof conforming with the inner diameter of the collar 4. Threadably engaging with the upper ends of the standards 5 are oppositely disposed elbow-couplings 6, 7, each provided at its upper end 100 and on its inner face with threads 8. The elbows 6 and 7 have the upper ends thereof connected together by a combined support and lubricant reservoir forming means referred to generally by the reference character 9, and which consists of a horizontally disposed tubular member 10 having peripheral threads 11 at each end for engagement

with the threads 8 of the elbow couplings. The member 10 is closed at each end by a plug 12, and centrally of its top the said member 10 is provided with an opening 13 forming a lubricant filling opening or inlet. The bottom of the member 10, at a point between its vertical median and each end is formed with an opening and one of said openings is indicated at 14 and the other at 15. The member 10 provides a reservoir 15', which is adapted to contain a body of lubricant 16 and a body of waste 17.

When employing a hold-up or a hold-down a tubular carrier 18 is used. The carrier 18 when a hold-down is employed is suspended from the member 10 and when a hold-up is employed extends above said member 10. When the carrier 18 is used in connection with a hold-down, or a hold-up it is mounted in a manner whereby it can operate in an oscillatory manner due to the reciprocation of the pair of pull rods with which it is associated.

Associated with the carrier 18, when a hold-down is employed, is a gudgeon, referred to generally by the reference character 19 and shown in Figures 1 and 2. The gudgeon 19 includes a head piece 20, formed of a cylindrical upper portion 21 provided with a chamber 22, a tapered intermediate portion 23, a cylindrical lower portion 24 of uniform diameter and a pair of oppositely disposed cylindrical trunnions 25, 26 formed integral with the ends of the cylindrical portion 21. The gudgeon 19 is furthermore provided with an axially arranged bore 27 which extends from the chamber 22 to the lower end of the end portion 24. The intermediate part 23 is provided with a pair of oppositely extending channels 28 which open into the bore 27 and also open at their outer ends at the periphery of the part 23. Formed integral with the intermediate part 23, is a pair of oppositely disposed lubricant collectors and directors 29, for collecting and directing the lubricant to the ports 28. The combined collectors and directors project laterally from the intermediate part 23 at an upward inclination and extend to a point below the inner portions of the trunnions 25, 26. Each trunnion is formed with a lengthwise disposed opening gradually decreasing in diameter from the outer end to the inner end of the trunnion. The openings formed in the trunnions are indicated at 30 and at their inner ends communicate with the chamber 22. The part 24 of the trunnion 19, is extended into one end of the carrier 18, and detachably connected therewith by a bolt and nut 31'. The bolt is disposed diametrically with respect to the part 24 of the trunnion and the carrier 18. The part 24 and carrier 18 are provided with suitable openings for the pas-

sage of bolts. When the part 24 of the trunnion 19 is secured to carrier 18, the combined collectors and directors extend over the edge of the carrier 18, as well as project laterally from the carrier, see Figure 1. The diameter of each trunnion with respect to the part 21 of the gudgeon 21 is such as to provide a shouldered portion 32 at the point of joinder of a trunnion with the part 21 of the gudgeon 19.

Associated with each trunnion of the gudgeon 19 is a bearing element, and as each of said elements is of the same construction, but one will be described, as the description of one will apply to the other. Each of said elements is indicated generally by the reference character 31 and consists of a body portion 32 formed with an opening 33 for the reception of the trunnion. The opening 33 is of greater length than the length of the trunnion, the latter terminating at a point inwardly with respect to the outer end of the opening. The body portion 32 is formed with a pair of lengthwise extending peripheral flanges 34, each formed with a vertically disposed opening 35. The top of the body portion 31 is formed with a concavity 36 which provides a seat for the reception of the member 10. The body portion 31 centrally of the concavity is formed with a port 37 which communicates with the interior of the member 10 whereby lubricant can be supplied from the reservoir 15' to the opening 33.

The elements 31 are secured to the member 9, by yokes 38; one yoke for each element 31, and each yoke extends down through the openings 35 formed in the flanges 34 of that element with which the yoke 38 is associated, and the ends of the yoke carry clamping nuts 39 which abut against the bottom edges of the flanges 34. When the elements 31 are arranged in active position to provide bearings for the trunnions of the gudgeon 19, the said elements 31 abut against the lower face of the member 10, see Figure 1. The elements 31 are fixedly secured to the member 10 and in connection with the gudgeon 19, couple the carrier 18 therewith, and the trunnions of the gudgeon 19 permit of the carrier 18 oscillating on the operation of the pull rods.

When employing the hold-down, the lower end of the carrier 18, has connected therewith, a stirrup box referred to generally by the reference character 40 and which consists of an oval-shaped body portion 41 formed with an oval-shaped opening 42 to provide a pair of hooks 43 which are oppositely disposed with respect to each other and arranged in spaced relation. The ends of the opening 42 form seats 44 for the stirrups. The spacing of the hooks 43 from each other provide a clearance 45 for the entrance of a stirrup. Formed integral with the body

portion 41 is a shank 46 which extends into the lower end of and is connected to the carrier 18 by the holdfast device 47. The body portion 41 in proximity to each side 5 of the shank 46 is provided with a vertical port 48 for the passage of lubricant into the opening 42 for lubricating the stirrups. The lubricant passes down between the inner face of the carrier 18 and the periphery of 10 the shank. A pull rod is indicated at 49 and which has connected thereto a combination clamp 49' carrying a stirrup 50 mounted in one of the seats 44 of the box 40.

When using the hold-up, the gudgeon employed in connection with the carrier is of a slightly different arrangement from the gudgeon 19, and this statement also applies to the bearing for the trunnions forming a part of the gudgeon and it also applies to 20 the stirrup box employed in the hold-up. The gudgeon which is used in the hold-up is referred to generally by the reference character 51 and is constructed similar to the gudgeon 19, with this exception that the 25 gudgeon 51 is not provided with the ports 28 and combined collectors and deflectors 29. The trunnions of the gudgeon 51 are indicated at 52. When using the hold-up, the bearings indicated generally by the reference 30 character 53 are employed for the trunnions 52 of the gudgeon 51. Each bearing or bearing element 53 is constructed similar to a bearing element 31 with this exception, that the element 53 is not provided with a 35 port 37; but it may be provided with a port 37. The stirrup box employed in the hold-up is referred to generally by the reference character 54 and includes a body portion 55, having an oval-shaped opening 56 forming 40 a pair of spaced oppositely disposed hooks 57. The hooks 57 are spaced from each other to provide a clearance 58 for the insertion of the stirrup 50. The ends of the opening 56 provide seats 58' for the stirrups. The 45 body portion 55 has a lubricant reservoir 59, and also a port 60 for the passage of lubricant from the reservoir 59 into the opening 56 for the purpose of lubricating the stirrups. Formed integral with the body portion 55 is a depending shank 61, having an 50 opening 62 extending from one end to the other thereof and said opening also extends through the body portion 55 and communicates with the opening 56. The opening 62 55 gradually increases in diameter from its upper to its lower end and provides means for establishing communication between the opening 56 and the interior of the carrier 18. The shank 61 is secured to the carrier 18 by 60 the holdfast device 63. The lubricant passing down through the carrier 18 will enter the gudgeon and when sufficient quantity has been collected in the chamber 22 will pass into the trunnions and from there into

the openings 33 and provide for the lubrication of the trunnions. The bearing elements 65 53 are secured in position by the yokes 38. The bearing elements 53 when secured in position are mounted on the top of the member 10 and the gudgeon is positioned over 70 the opening 13. A reservoir 59 is positioned at each end of the body portion 55 and a port is associated with each reservoir so that lubricant can be supplied to the opening 56. The stirrups when coupled with the box 75 54 act as means for closing the outlet ends of the port 60 in a manner to prevent too free discharge of lubricant from a reservoir 59.

Each bearing element 31 or 53 is formed 80 with a projection or boss 53' seating in an opening 14 or 15, and which serves as a key or locking device to prevent slippage or mis-alignment of parts when assembled. The ports 37, of the bearing elements 31 extend 85 through the projections or bosses.

Referring to Figure 8, which illustrates a single stirrup box 60', which serves as a single stirrup box in connection with box 40 and when used it is bolted directly to the 90 carrier 18. When the box 60' is employed, one pull rod with its connected stirrups is attached thereto. This is placed on the opposite side from the direction of pull rod in such a manner that carrier 18 extends 95 through the stirrup. When assembled in this manner, the bolts attaching box 60' are not effected by tension of pull rods, due to the carrier 18 extending through stirrup and used to prevent lateral movement of box 60'. It will be noted that when using box 60', 100 half of stirrup box 40 will remain idle, unless two rods are attached to that side of the apparatus.

It may be necessary, when holding up, to 105 omit standards 5, and provide direct connections between elements 6 and 4 and 7 and 4.

A hold-up or hold-down in accordance with this invention, for use in connection with oil or gas well pumping apparatus, provides an unusually rigid construction and a more accurate means for lubricating the 110 bearings of the oscillatory carrier, as well as for lubricating the stirrups when coupled to the carrier, therefore it is thought the many advantages of a hold-up or a hold-down in accordance with this invention, can be readily understood, and although the preferred embodiment of the invention is as 115 illustrated and described, yet it is to be understood that changes in the details of construction can be had which will fall within the scope of the invention as claimed.

What I claim is:

1. A device for the purpose set forth comprising a supporting structure, a pair of spaced bearing elements adapted to be se-

cured thereto, a gudgeon including trunnions journaled in said bearings, a carrier attached to said gudgeon, stirrup coupling means attached to the carrier, and said supporting structure, bearing elements, gudgeon and carrier having coacting means for supplying lubricant to said trunnions and coupling means.

2. A device for the purpose set forth comprising an anchored supporting structure, a pair of spaced bearing elements secured thereto, an oscillatory gudgeon provided with a pair of trunnions journaled in said elements, a carrier having its inner end overlapping and secured to said gudgeon and extended therefrom, said carrier bodily movable with said gudgeon, a stirrup coupling element secured in the outer end of said carrier and extended therefrom, and said structure, bearing elements, gudgeon and carrier having coacting means for supplying lubricant respectively to said trunnions and stirrup coupling element.

3. In a hold-up or hold-down for use in connection with well pumping apparatus a stirrup box comprising a body portion and a reduced shank disposed centrally with respect to the body portion, said body portion formed with an oval-shaped opening extending transversely thereof and providing a pair of oppositely extending hooks, said hooks spaced from each other to provide a clearance for entrance to said opening to position the stirrups, and said body portion provided with plural means for storage of and the passage of lubricant to said opening to lubricate the stirrup or stirrups mounted therein.

4. In a hold-up or hold-down for oil pumping apparatus an inverted U-shaped supporting structure, a pair of spaced bearing elements anchored to the top of said structure, oscillatory means journaled in said bearings, a stirrup box secured in and extended from said means at the outer end thereof and provided with a transverse opening to form a pair of opposed seats for the reception of a pair of oppositely extending stirrups, and said structure, bearing elements and oscillatory means having coacting means for lubricating the said oscillatory means and the stirrups within said box.

5. A device for the purpose set forth comprising a supporting structure provided with a lubricant reservoir, a pair of spaced bearing elements secured to the upper end of said structure, an oscillatory gudgeon including spaced trunnions journaled in said elements, said structure and elements having coacting means for supplying lubricant to said trunnions, a carrier attached to said gudgeon and bodily movable therewith, stirrup coupling means secured to said carrier, and said gudgeon and carrier provided

with coacting means for supplying lubricant to said coupling means.

6. A device for the purpose set forth comprising a supporting structure provided at its top with a lubricant reservoir, a pair of spaced tubular bearing elements each open at its inner and its outer side, said elements secured to the top of said structure, an oscillatory gudgeon including hollow spaced trunnions journaled in said elements, said trunnions having their outer ends spaced inwardly from the outer sides of said elements, said structure and elements having coacting means for supplying lubricant to said trunnions, a carrier secured to said gudgeon and bodily carried therewith, stirrup coupling means secured to said carrier, and said gudgeon and carrier having coacting means for supplying lubricant to said coupling means.

7. A device for the purpose set forth comprising a supporting structure provided with a lubricant reservoir, a pair of spaced bearing elements secured to the upper end of said structure, an oscillatory gudgeon including spaced trunnions journaled in said elements, said structure and elements having coacting means for supplying lubricant to said trunnions, a carrier attached to said gudgeon and bodily movable therewith, stirrup coupling means secured to said carrier, said gudgeon and carrier provided with coacting means for supplying lubricant to said coupling means, and said gudgeon provided with means for collecting and directing lubricant dripping from said elements into said carrier.

8. A device for the purpose set forth comprising a supporting structure provided at its top with a lubricant reservoir, a pair of spaced tubular bearing elements each open at its inner and its outer side, said elements secured to the top of said structure, an oscillatory gudgeon including hollow spaced trunnions journaled in said elements, said trunnions having their outer ends spaced inwardly from the outer sides of said elements, said structure and elements having coacting means for supplying lubricant to said trunnions, a carrier secured to said gudgeon and bodily carried therewith, stirrup coupling means secured to said carrier, said gudgeon provided with means for collecting and directing lubricant dripping from said elements into said carrier.

9. A device for the purpose set forth comprising a supporting structure provided at its top with a lubricant reservoir, a pair of spaced tubular bearing elements secured to the top of said structure, an oscillatory gudgeon including spaced trunnions journaled in said elements, said structure and elements having coacting means for supplying lubricant to said trunnions, a carrier secured to said trunnions and bodily movable there-

with, and stirrup coupling means secured in the outer end of said carrier and extended laterally in opposite directions therefrom.

10. A device for the purpose set forth comprising a supporting structure formed with a hollow top to provide a lubricant chamber, a pair of spaced, tubular bearing elements secured to said top, said elements and said structure having coacting means 10 for establishing communication between the interior of the elements and said chamber, a gudgeon including trunnions journaled in said elements, a carrier attached to said gudgeons, and stirrup coupling means secured to the carrier and formed with a transversely extending opening to provide a plurality of opposed stirrup seats.

11. A device for the purpose set forth comprising a supporting structure, an oscillatory gudgeon including trunnions, bearing elements for said trunnions secured to said supporting structure, a carrier attached to said gudgeon, a split oval-shaped stirrup coupling means including a shank fixedly secured to 25 said carrier, and said structure, bearing means, gudgeons, carrier and stirrup coupling means having coacting means for lubricating the trunnion and for the stirrups coupled with the carrier.

30. 12. In a hold-up or hold-down for use in connection with oil pumping apparatus a supporting structure, a tubular carrier, an oscillatory gudgeon connected with said structure and extending in and secured to 35 one end of said carrier, a coupling element including a body portion provided therein with a pair of opposed stirrup receiving seats, said element further including a shank disposed centrally with respect to said body 40 portion and extending into and secured to the other end of said carrier, and said structure, gudgeon, carrier and element having coacting means for lubricating the gudgeon and the stirrups engaging said seats.

45. 13. A device for the purpose set forth com-

prising a supporting structure, a hollow, oscillatory gudgeon including hollow trunnions, bearing elements for said trunnions secured to said supporting structure, said elements being tubular and projecting from 50 the outer ends of the trunnions, a hollow carrier attached to and opening into said gudgeon, said gudgeon providing for the passage of lubricant therethrough to said carrier, a split oval-shaped stirrup coupling 55 means including a shank fixedly secured to said carrier, said means receiving lubricant from the carrier, said structure including a lubricant reservoir, and said structure, bearing elements and gudgeon having coacting 60 means for the passage of the lubricant from said reservoir for supplying lubricant to said trunnions and into said gudgeon.

14. A device for the purpose set forth comprising a supporting structure, a hollow, oscillatory gudgeon including hollow trunnions, bearing elements for said trunnions secured to said supporting structure, said elements being tubular and projecting from 65 the outer ends of the trunnions, a hollow 70 carrier attached to and opening into said gudgeon, said gudgeon providing for the passage of lubricant therethrough to said carrier, a split oval-shaped stirrup coupling means including a shank fixedly secured to 75 said carrier, said means receiving lubricant from the carrier, said structure including a lubricant reservoir, and said structure, bearing elements and gudgeon having coacting 80 means for the passage of the lubricant from said reservoir for supplying lubricant to said trunnions and into said gudgeon, said gudgeon provided with means for receiving the drippings of lubricant from said elements and for discharging it into the interior of the 85 gudgeon.

In testimony whereof, I affix my signature hereto.

CLOISE H. BALDWIN.
